UNITED STATES PATENT OFFICE.

WILLIAM H. JORDAN, OF BROOKLYN, NEW YORK; AND GEORGE T. HANCHETT, OF HACKENSACK, NEW JERSEY, ASSIGNEES TO JORDAN AUTOMATIC SIGNAL COMPANY, OF NEW YORK, N. Y., A CORPORATION OF NEW YORK.

RAILWAY-SIGNAL.

No. 866,281.

Specification of Letters Patent.

Patented Sept. 17, 1907.

Application filed June 14, 1905. Serial No. 265,209.

To all whom it may concern:

Be it known that we, WILLIAM H. JORDAN, a citizen of the United States, residing in Brooklyn, county of Kings, and State of New York, and GEORGE T. HANCHETT, a citizen of the United States, residing in the town of Hackensack, county of Bergen, and State of New Jersey, have invented certain new and useful Improvements in Railway-Signals, of which the following is a description.

10 Our invention relates to that class of signals used upon electric railways which derive their power from the same source as that employed to propel the cars, but the invention may be applied to steam roads or to electric roads with the signals actuated by current other than that used to propel the cars.

15 The object we have in view are, the production of means for actuating the semaphore in a danger or safety position as may be desired; the displaying of red or white lights as the exigencies of the service may demand; the counting of the number of cars which may pass the signal station; the sounding of an audible alarm at any point desired; the provision of a reserve system of lamps which are cut in in the event of one set failing; the visual indication to motormen or inspectors 20 that such lamps have failed and others have been substituted; the insuring that the different mechanism will promptly respond to the signals; the provision that the cars will be positively stopped in the event of the visual signal failing, or the motorman or engineer neglecting 25 to heed such signal; and the provision for actuating the signals irrespective of the voltage on the line. We attain these objects by the mechanism illustrated in the accompanying drawings, in which

Figure 1 is a front view of a portion of the apparatus, 30 partly in section and partly diagrammatical. Fig. 1^a is a sectional view thereof. Fig. 2 is a diagram of the lamps and the means for automatically cutting in a new set in the event of the set ordinarily used becoming disabled. Fig. 3 is a diagrammatical view of the actuating solenoids and counting solenoid. Fig. 4 is a view in perspective of a portion of the apparatus in use. Fig. 4^a is a diagrammatical view of three stations, showing the circuits. Fig. 5 is a diagrammatical view of the solenoids, showing the parallel connections. Fig. 45 5 is a perspective view, enlarged, of one form of bracket for supporting the trolley wire. Fig. 7 is a sectional view thereof, taken on the lines 7-7 of Fig. 6. Fig. 8 is a view, partly in section, of the counting mechanism and its actuating magnet. Fig. 9 is a diagram showing 50 the action of the actuating solenoids. Fig. 10 is a diagrammatical view showing the means for positively applying the brakes to the car, in the event that the signal is not seen or heeded, and Fig. 11 is a diagram-

matical view showing the arrangement of the circuits for the structures shown in Fig. 10.

55

In all the views like parts are designated by the same reference characters.

The motive power of the device comprises two magnets or coils, preferably of the solenoid type, set opposite to each other and acting upon the same plunger or 60 core. One of these magnets, when energized pulls the plunger in one direction, and the other pulls it in the opposite direction, the motion of the plunger being transmitted by appropriate mechanical means to a 65 semaphore and to a color target, the semaphore being actuated thereby to show danger or safety positions, and the color target being thrown in front of the signal lamps or removed therefrom so as to cause them to shine red or white through appropriate bull's eyes in the casing.

70

The casing 11 carries the two actuating solenoids D and S in opposed relation and actuating the plunger A. In the particular embodiment of the invention illustrated, the solenoid D is designed to move the plunger to actuate the semaphore and color target and 75 move them to the danger position, the solenoid S acting in the opposite direction to move them to the safety position. Each solenoid is connected to the circuit in such a manner, as will be described, as to first energize the solenoid D, causing it to attract the plunger 80 and move the semaphore and color target to the danger position; upon the car passing the danger point, the circuit will be completed through the solenoid S, energizing it and retracting the plunger, causing the semaphore and color target to move to the safety position. 85

The semaphore 12 is preferably mounted upon a shaft 13 journaled within the casing 11 and provided with a pinion C. This pinion C meshes with a rack 14 formed upon the plunger A and by means of which it will be rotated upon the reciprocation of the plunger and the 90 shaft 13 and semaphore 12 given a quarter turn so as to display its edge or side, as desired. The color target 15, which is preferably in the form of a frame with a window of colored glass, is mounted upon a shaft 16 carrying a pinion B, which also meshes with the rack 95 14. Upon the reciprocation of the plunger A and through the agency of the rack 14, pinion B and shaft 16, the target will be moved to cause it to cover the signal lamps or expose them, and thereby change their color from white to red, as necessary.

100

We prefer to make the rack 14 cut with circular teeth or formed upon the cylindrical plunger A. By this means a feather or guideway to prevent turning of the plunger will not be required, the latter may be adjusted with great ease as the pinions C and B will 105 mesh at any portion of the circumference of the rack,

and furthermore such a form of rack is cheaper to make than two racks at right angles to engage with the pinions B and C.

The boxes 11 are placed at suitable intervals, and 5 the solenoids D and S are connected to circuit closers upon the trolley wire or at other points, as may be desired, in such a manner that each of the solenoids D will be first energized momentarily to cause the attraction of the plunger A just as the car is entering the 10 danger zone, and at the proper point the solenoid S will be energized and the plunger retracted.

We have found in practice that solenoids which are properly wound to handle the high voltage of street railway practice, retain such an amount of residual 15 magnetism that the opposing solenoid cannot attract the plunger against such residual magnetism during the short period of time which it is energized. We have provided means for doing away with this residual magnetism. Such means preferably comprises additional coils surrounding the main coils and adapted to be energized at the proper time. In Fig. 3 these coils are shown and designated by the characters D' and D². The coil D' surrounds the coil S, and the coil D² surrounds the coil D. These coils are preferably connected in series in such a manner that the coil D' will be energized simultaneously with the coil D, and the coil D² will be energized simultaneously with the coil S.

The circuits are as follows: 17 is the main trolley wire; 30 18 the circuit closer for the danger position; 19 is the circuit closer for the safety position. From the circuit closer 18 the current passes through the wire 20 to the coil D', and from thence through the wire 21 to the coil D, and from there through the wire 22 to the ground 35 23, thus simultaneously energizing the coils D' and D. From the circuit closer 19 the current passes through the wire 24 to the coil D², and from thence through the wire 25 to the coil S; from the coil S it passes through the wire 26 to the ground 23, thus simultaneously 40 energizing the coils D² and S. The circuits may be arranged in any other suitable manner.

Instead of arranging the coils in series, they may be arranged in parallel, as shown in Fig. 5. In this view the current passes through the contact 18 to the wire 45 27, where it branches, part flowing through the solenoid D to the ground 23, and part through the wire 28 and through the solenoid D' and thence through the wire 29 to ground. The current passes from the circuit closer 19 through the wire 30, and, branching, passes 50 through the coil S to ground and through the wire 31 to the coil D², thence through the wire 32 to ground. By these means the coils D and D' will be first energized, the coil D' neutralizing any magnetism remaining in the coil S and thoroughly demagnetizing it, permitting the 55 plunger to be drawn within the coil D by the momentary impulse of the current passing through it. Upon the current passing through the coil S, it will also pass through the coil D², completely deenergizing the coil D and permitting the plunger to be moved in the opposite direction.

Any form of circuit closer may be employed, but that illustrated in Figs. 6 and 7 is preferred. The device is adapted to be combined with the trolley wire support 33. The device comprises a plate 34, which may 60 be supported by any suitable means, such as bolts 35,

from the support 33. These bolts are surrounded by suitable insulation 36 and a spacing collar 37, so that it will be held a sufficient distance away from the support 33 so that all danger of short-circuiting will be prevented. To the plate 34 is secured a leading-off wire 38, 70 which may be either of the wires 20 or 24 or 27 or 30. The parts are so proportioned and arranged that the trolley 39, in passing along the wire 17, will come in contact with the plate 34, bridging the space between it and the wire, short-circuiting at that point. This 75 will cause an impulse to pass over the wire 38.

We find in practice that the movement of the plunger A is extremely rapid, and if the semaphore and color target be directly connected to their supports, that they are liable to become damaged or broken by the sudden 80 movement of the actuating means. We provide a means for preventing the sudden movement of the plunger from harming the other mechanism, such means being in the form of a spring connection. In connection with the semaphore we prefer to make the 85 shaft 13 in two parts, one telescoping within the other at 40. The two parts are connected together by a coiled spring 10, which will act by torsion and be twisted by the sudden movement of the lower portion of the shaft 13, thus absorbing any shock caused by the sudden 90 movement of the latter. In connection with the color target we prefer to mount it loosely upon the shaft 16. It is actuated by the shaft through the agency of the spring 9, which is connected to the target at one extremity, while its other end is connected to a short arm 95 41 secured to and rotating with the shaft 16. The spring 9 is sufficiently strong to pull the target to its positions, yet will yield enough to prevent the sudden movement of the shaft 16 from injuring the target. Other means may be devised to prevent shock between 100 the moving elements and the semaphore and target, such means generally comprising a lost motion device of some sort.

In connection with the signals already described, we prefer to use a bell, as V, which may be arranged within 105 a circuit 42, which will comprise a battery or other source of current 43. This bell will be of service at crossings, roads, switches or stations. One end of the circuit 42 can be connected to an arm G, insulated from the support 11 by insulation 44, and adapted to be engaged by a collar K upon the plunger A when the latter is moved to the danger position within the coil D. The other end of the circuit 42 may be connected to the support 11, if the latter is made of metal. If the support should be made of wood, or some other poor conductor 110 of electricity, then that end of the circuit 42 should be connected directly to the plunger A. The battery 43 will continuously ring the bell V so long as the plunger A is attracted within the coil D, and will thereby serve 115 as an audible signal for indicating danger.

In connection with the signals already described, we find it useful to employ an indicator which will indicate the number of times that the device is actuated. This indicator may be operated by a coil J, which should be arranged within the circuit 20, which 120 will include the danger magnet D, or it may be placed in the safety magnet circuit. There is no object in connecting the coil within the common circuit of these magnets, as by such an arrangement the device would indicate twice for the passage of every car, 125 130

- unless such a counter were employed as would indicate but once for each two pulsations. The details of the indicator are shown in Fig. 8. The coil J may be supported upon a plate 45, and includes a core 46. 5 Upon the core 46 is a pin 47 having a slot 48. Through the slot 48 passes an arm 49 connected to and actuating a recorder 50. The recorder may be of any well known commercial type, and is arranged to indicate every time the lever 49 is elevated and depressed.
- 10 In order to insure that the lamps will always be properly burning, we prefer to arrange them in two sets, 5 and 6, and 7 and 8. In connection with these lamps, which are the signal lamps, are provided the protective lamps 2, 3 and 4. These protective lamps 15 are shown as arranged in series with either of the two sets of lamps 5 and 6 or 7 and 8, but they may be arranged in two sets, each set in series with a set of signal lamps. Automatic means are provided for cutting out one set of lamps should they become disabled, and 20 cutting in the other set. These means may comprise a cutout or relay R, which as shown consists of a magnet 51 actuating a lever 52 which is normally elevated by means of a spring 53. The lever 52 may rest upon a stop 54 when the magnet 51 is energized. Upon the 25 magnet 51 being deenergized, the spring 53 will elevate the lever 52 and cause it to engage with an insulated contact 55. The circuit from the protective lamps passes through a wire 56, where it divides, part being connected to the magnet 51, and from thence to 30 the wire 59, which is connected to the lamps 5 and 6; the other part connects with the base of frame 60 of the cutout, which frame is electrically connected to the lever 52. As shown in Fig. 3, the lamps 5 and 6 are 35 presumed to be burning properly; the magnet 51 will therefore be energized, attracting the lever 52 and breaking the contact between it and the contact 55, thereby cutting out the lamps 7 and 8. If one of the lamps 5 or 6 becomes disabled, the circuit will be 40 broken at that point, thereby deenergizing the magnet 51, allowing its armature to be retracted by the spring 53, and causing it to engage with the contact 55, which will then put the lamps 7 and 8 in circuit.
- In order to form a means for indicating that the lamps 5 and 6 have become disabled, we prefer to 45 arrange them so as to shine through a bull's eye of different shape than the lamps 7 and 8 shine through. Any form of bull's eye may be employed, that illustrated in Fig. 4 comprising a single long opening 61 for the lamps 5 and 6, and separate and distinct bull's 50 eyes 62 and 63 for the lamps 7 and 8. The difference in appearance between the light shining through the different shaped bull's eyes will indicate to the motormen or others that one set of lamps has become disabled, and opportunity may thereby be had to repair 55 them before the lamps 7 and 8 will have had a chance to also become disabled.
- Fig. 4^a is illustrative of the manner of connecting a number of different signal stations; three are shown indicated by the characters 64, 65 and 66. The car 60 will pass in the direction of the arrow, that is, from the right to the left. Upon reaching the contact shoe E¹ the current will pass along the wire W¹ to the demagnetizing coil of the danger magnet of the station behind it (not shown) and through the main coil of the 65 safety magnet of such station, setting the parts to the

safety position. The current will branch and pass through the demagnetizing coil D¹ of the station 64 and also through the main danger coil D at such station setting the parts to danger. They will remain in such position until the trolley comes in contact with the 70 circuit closer E². The current will then pass through the wire W², through the demagnetizing coil D² and through the safety coil S of the station 64, which will move the semaphore and target of such station to safety. At the same time the current will pass through 75 the demagnetizing coil D¹ and danger coil D of the station 65 moving the parts to the danger position. The same action will be repeated when the trolley reaches the contact E³, the current passing over the wire W³ and through the demagnetizing coil D² and safety coil 80 S of the station 65 setting the parts to safety and at the same time will pass through the demagnetizing coil D¹ and danger coil D of the station 66 setting the parts of such station to danger.

We have found that in electric railway systems the 85 electric pressure will vary widely, sometimes as much as fifty per cent, and in order that the magnets shall be operative at any of the pressures which may exist on the line they are so designed that at the lowest possible line pressure which is used their cores will always 90 remain saturated. Under this condition it is evident that any higher pressure will produce no difference in the magnet action, and by this construction the signal is enabled to work reliably upon all of the pressures 95 which are found in practice.

Fig. 9 illustrates a chart indicating the construction of the magnet. 67 represents abscissæ and 68 ordinates, the abscissæ representing difference of potential and the ordinates magnetism. The curve 69—70 represents the stages of magnetism resulting from certain 100 pressures. This curve rises gradually up to a point of complete saturation, and then becomes nearly horizontal, as between the points 71 and 72. This line represents the point of complete saturation, anything below such line being the point of incomplete saturation. The ordinary form of magnet is adapted to be 105 operative in stages of incomplete saturation, as between the points 73 and 71. At the point 73 there may be insufficient magnetism to actuate the moving parts of the semaphore. 110

By our invention we arrange the magnets to operate between the points 71 and 72, which will represent the greatest variations in pressure in the line. The points 71 and 72 represent points of complete saturation of the core, and consequently the magnet will operate 115 with maximum power, even when energized by a minimum working current. On electric railway circuits the voltage varies very widely from about 250 to 550 volts. If the signaling magnet is so constructed that its core shall be saturated when its potential bobbins 120 have a voltage of 250, their action magnetically will not be materially different when the voltage is 500. It is true that the principal part of the curve which rates the flux and which in turn is a function of the magnetic pull is not quite parallel to the axis of the 125 abscissæ, but it is nearly so, and if the magnet be designed to be saturated at 250 volts, its magnetic action will be substantially the same as at all higher voltages. If on the other hand, as has been common heretofore, the magnet is designed so as to work when the rated 130

voltage of the line, 550 or 500 volts, as the case may be, is impressed upon it, then when 250 volts are on the line, the magnet not being saturated, will work on the steep part of the curve, between 73 and 71, and will rapidly fall in flux to a much lower value, and is extremely likely to fail to operate. This is a very real trouble which we have encountered ourselves, and which has been encountered before; and which is obviated by the device of designing the magnet so as to be saturated or 10 nearly so at the time that the lowest potential ever found upon the line obtains.

Absolute saturation and approximate saturation are impossible of specific definition, but for the purposes of illustration, the following table is appended. The 15 lowest potential that obtains on the line will produce in the operative magnets the following flux values per square inch with different materials:

Annealed wrought iron.....	100,000 lines
Soft cast iron.....	97,500 "
20 Mitus iron.....	90,000 "
Cast iron containing 6.5% aluminium.....	45,000 "
Ordinary cast iron.....	40,000 "

In Figs. 10 and 11 is shown a structure for automatically applying the brakes, in the event that the car is 25 allowed to proceed beyond the danger point. Two solenoids 74-75 are arranged to act upon a plunger or armature 76, the said plunger actuating a device which will engage with the three-way cock or other device for 30 controlling the air brake. As shown in Fig. 10, the plunger 76 is provided with the rack 77 which engages with the pinion 78, the said pinion in turn oscillating a lever 79. This lever may be arranged between the rails 80, or at any other convenient point, so that when 35 elevated to the dotted line position shown in Fig. 10 it will engage with the lever 81 of the three-way cock, attached to the air brake system 82, of the car 83. The lever 79 when oscillated to the solid line position shown in Fig. 10 will clear the lever 81 and not actuate the latter. The lever 79 is preferably arranged to be moved 40 beyond the vertical position and when so moved will abut against a stop 84 so that it will be rigidly supported in position when engaged by the moving lever 81 carried by the car. The coils 74 and 75 may carry 45 magnetizing coils 85-86 surrounding the coils 74-75 respectively.

As shown in Fig. 11 the coils 74-75 and lever 79 are arranged in advance of the signal actuating coils D-S, the exact distance that they are arranged in advance 50 being varied as requirements dictate. The coils 74-75 may be arranged in parallel with the coils D-S as shown in Fig. 11, but the arrangement of circuits may be varied as desired, or found necessary.

In Fig. 11 the coil 74 is connected through a circuit 55 embracing the wires 87 and 88, passing out through the return 89. This coil will therefore be in parallel with the coil D. The coil 75 is connected to the circuit which includes the wires 90 and 91. By this construction when the coil D is energized the coil 75 will also 60 be energized, and the stop 79 moved from the solid line position (Fig. 10) to the dotted line position. The coil 74 will be in parallel with the coil S, and when the semaphore is moved to the safety position the coil 74 will be energized, attracting the plunger and moving 65 the stop 79 to the solid line position (Fig. 10). The

deenergizing coils 85 and 86 are connected as shown in Fig. 11 so that the coil 85 will be energized the instant the coil 75 is energized, and the coil 76 will be energized at the same time the coil 74 is energized, so that the main coils 74 and 75 will be freed from their residual 70 magnetism.

The solenoid disclosed herein and the arrangement of the deenergizing means disclosed are not claimed in this application for patent but forms the subject matter of an application for patent filed on the 31st day of 75 May, 1907, Serial No. 376,675.

What we claim as new and desire to secure by Letters Patent is

1. In a railroad signal operated by electro-magnetic means, the combination of a coil and a core, an actuating plunger connected to the core and connecting the parts to be moved, and flexible mechanical connections between the actuating plunger and the parts to be moved.

2. In a railroad signal operated by electro-magnetic means, the combination of a double system of signal lamps 85 and a relay, so connected to the circuit as to cut in one system of signal lamps when the other system is disabled, such system of signal lamps shining through bull's eyes of different shapes.

3. In a railroad signal operated by electro-magnetic means, the combination with a pair of opposed magnets, a plunger connecting the cores thereof, the said plunger having cylindrical teeth forming a circular rack, pinions engaging with said teeth, and signaling means operated by the movements of the pinions, substantially as described.

4. In a railroad signal operated by electro-magnetic means, the combination with a plunger and actuating magnets, of a semaphore and connections between the plunger and semaphore, such connections comprising lost motion 100 parts.

5. In a railroad signal operated by electro-magnetic means, the combination with a plunger and actuating magnets, of a semaphore and spring connections between the plunger and semaphore.

6. In a railroad signal operated by electro-magnetic means, the combination with a plunger and actuating magnets, the said plunger carrying a rack, a semaphore, a shaft for rotating the semaphore, the said shaft having a pinion engaging with the rack, the shaft being divided and 110 a spring connecting the parts.

7. In a railroad signal operated by electro-magnetic means, the combination with actuating magnets and a plunger, the said plunger having teeth forming a rack, pinions engaging with the teeth and connections between the pinions and the signaling device, such connections comprising lost motion parts.

8. In a railroad signal operated by electro-magnetic means, the combination with the actuating magnets, a rack moved by such magnets, a pinion engaging with the 120 rack, connections between the pinions and the signaling device, such connections comprising lost motion parts.

9. In a railroad signal operated by electro-magnetic means, the combination with the actuating magnet and the plunger, a rack, pinions engaging with the rack and 125 moved by the plunger, a signaling device and spring connections between the pinions and signaling device.

10. In a railroad signal operated by electro-magnetic means, the combination with the actuating magnet and plunger, a rack moved by the magnet, a pinion engaging 130 with the rack, a semaphore, a shaft for actuating the semaphore, connections between the shaft and the pinion and a spring interposed between the pinion and the semaphore.

11. In a railroad signal operated by electro-magnetic means, the combination with the actuating magnets, a plunger actuated thereby, a rack, a pinion engaging with the 135 rack, the said pinion being mounted upon a shaft, a color target loosely mounted upon the shaft and an arm secured to the shaft and a spring connecting the arm and a color target.

12. In a railroad signal operated by electro-magnetic

means, the combination with a magnetically actuated signal, of a stop actuated by electro magnetic means in circuit with the signal actuating means, such electro magnetic means positively moving the stop into and out of the path of the controlling mechanism of the brake of the moving car.

13. In a railroad signal operated by electro magnetic means, the combination with a magnetically actuated signal, of a stop actuated by electro magnetic means in circuit with the signal actuating means, such electro magnetic means being arranged in opposition and connected to the stop for positively moving the stop into and out of the path of the controlling mechanism of the brake of the moving car.

14. In a railroad signal operated by electro magnetic means, the combination with a magnetically actuated sig-

nal, the said signal comprising opposed solenoids and a positive stop for the car, the said positive stop comprising opposed solenoids and connecting the circuit with the signal solenoids, a plunger between the solenoids and acting upon them, the said plunger having a rack, and a pinion engaging with the rack and actuating the stop, the said stop being arranged to be engaged by the brake actuating mechanism of the car. 20

This specification signed and witnessed this 10 day 25 of June, 1905.
